Patented Feb. 21, 1922.

INVENTOR:
Ormond E. Hunt,

BY *P. A. —*

BY *S. Feltz* ATTORNEY

UNITED STATES PATENT OFFICE.

ORMOND E. HUNT, OF DETROIT, MICHIGAN, ASSIGNOR TO PACKARD MOTOR CAR COMPANY, OF DETROIT, MICHIGAN, A CORPORATION OF MICHIGAN.

MOTOR VEHICLE

1,407,418.

Specification of Letters Patent. Patented Feb. 21, 1922.

Application filed June 21, 1917. Serial No. 176,102.

To all whom it may concern:

Be it known that I, ORMOND E. HUNT, a citizen of the United States, and resident of Detroit, Wayne County, State of Michigan, have invented certain new and useful Improvements in Motor Vehicles, of which the following is a specification.

This invention relates to motor vehicles and particularly to the water circulation systems thereof.

More particularly the invention embodies a valve device or valve unit in which there is a thermostat adapted to operate the valve or valves.

One of the objects of the invention is to provide a valve device, preferably thermostatically controlled, in which the parts may be readily manufactured and assembled, and which may prove efficient and long wearing in operation.

Another object of the invention is to provide a thermostatically controlled valve device in which one of the valves is a non-seating valve thus making the valve and its port much easier to machine and permitting an advantageous arrangement of ports in the valve casing.

Another object of the invention is to provide a valve unit in which the casing has two outlet ports, one of which is larger than the other and both of which are controlled by valves closing against the direction of flow. By this arrangement, when the valve device is mounted as shown in the drawings herein, there is a greater tendency of the water flowing through the casing to open the larger port which permits the water to pass into the radiator.

Other objects of the invention will appear from the following description taken in connection with the drawings which form a part of this specification, and in which:

Fig. 1 is a vertical section through a valve device built in accordance with this invention and a part of the radiator of a motor vehicle in which the valve device is installed;

Fig. 2 is a view of the valve device or unit shown in Fig. 1, with the valves in another position, and

Fig. 3 is a transverse section on the line 3—3 of Fig. 2.

Referring to the drawings 10 represents the upper tank of a motor vehicle radiator, 11 is a filler tube therefor, and 12 represents

the upper part of the core of the radiator which is positioned below the tank 10. A casing 13 surrounds the tank part of the radiator for the purpose of protecting the tank and adding to the general appearance 60 of the radiator.

The valve device or unit which forms the principal subjects-matter of this invention comprises three principal parts, as follows:—a casing 14, a valve member 15, and a thermostat 16. The casing 14 has an inlet opening or port 17 whereby it receives the circulation water from the vehicle motor through a pipe 18 which is detachably connected to the casing as by bolts 19. A 70 circular opening 20 is formed in the rear face of the tank 10 of the radiator and a soft metal collar 21 is mounted therein and preferably secured to the tank as by soldering for the purpose of receiving the cylindrical part 22 of the casing 14. Thus the cylindrical part of the casing is inserted in the collar 21 until its flange 23 abuts against the collar 21 and it is then detachably secured to the collar as by a series of bolts 24. 80 This secures a tight joint between the casing and the tank 10 and securely mounts the valve unit in the central part of the tank under the filler tube 11. A baffle 25 is shown in the drawing to prevent the water issuing 85 from the forward end of the valve casing from splashing up into the filler tube.

The valve casing 14 is formed with two outlets, the large or main outlet 26 which permits water to flow from the casing directly into the tank 10 and from thence downwardly through the core 12 of the radiator, and the small or auxiliary outlet 27 nearer the rear end of the casing, which latter outlet is in the nature of a by-pass 90 adapted to pass around the radiator so that the water of the circulation system may pass back to the motor, preferably through the pump, without passing through the radiator and being cooled thereby. The circular 100 opening indicated at 28 may be termed the outlet port and it will be seen that the wall 29 of the chamber 30 which forms part of the outlet 27 and is positioned within the casing 14, are supported therein by several 105 ribs 31 past which the water flows from the inlet 17 to the main outlet or port 26 and the auxiliary outlet port 28. There are also leakage ports 32 at the forward end of the casing 14 through which a small quan- 110

22

tity of water may pass even though the main outlet 26 is otherwise closed. The valve member 15 above referred to is in the form of a cage with valves at its ends. The forward part of the cage is in the form of a disk or poppet valve 33 adapted to close the outlet 26 when the valve is in the position shown in Fig. 1. When the valve is moved forwardly as shown in Fig. 2, openings 34 in the cage permit the water to pass out through the port 26 into the tank 10, and during this movement of the valve the forward end of the cage is guided by the walls of the port 26. The rear part of the valve member 15 has a valve 35 connected to it as by a spider 36 threaded into the rear end of the cage part of the valve member. This valve 35 is slightly smaller than the port 28 in which it operates and it is mounted to slide upon or is guided by a rod 37 which is rigidly secured to the casing 14 as at 38. This rod 37 passes through the port 28 and is connected at its forward end to the rear end of the thermostat 16 above referred to, thus supporting the thermostat and facilitating the assembly of the unit. The valve and thermostat may be removed from the casing by removing a nut 39 by which the rod 37 is secured to the casing (see Fig. 2).

30 The thermostat 16 is mounted within the cage part of the valve member 15, being inserted therein before the spider 36 is secured to the cage, and the forward end of the thermostat is secured to the valve member by means of a stud 40 and nut 41.

It will be understood that the thermostat 16 contains a fluid such as alcohol or ether and that when cold it is in the contracted state shown in Fig. 1. The valve 33 is then closed on its seat so that the water will not flow into the tank 10 except such as may pass through the several leakage ports 32, and the valve 35 is wide open so that water will readily pass through the port 28 and outlet 27 into the by-pass above referred to. As the temperature of the water in the circulation system is raised due to the operation of the vehicle motor, the thermostat 16 expands to the position in which it is shown in Fig. 2 and the valve 33 is wide open to permit the water to pass into the tank 10 and to the radiator core 12, and the valve 35 has been moved against the direction of flow of the water through the port 28 to a position in that port so that it practically fills the opening and prevents the further flow of water therethrough. It will be seen that since the valve 35 is slightly smaller than the port 28 there may still be a small amount of leakage through that port, which in the operation of the vehicle is immaterial. By making this valve and port of this form however, these parts may be readily machined and with sufficiently wide limits to insure cheap production. More

over in the arrangement shown there is little or no danger of the valves becoming clogged by dirt as they are more or less self cleaning.

As shown, the expansion of the thermostat 16 or the forward movement of the valve member 15 is limited by the spider 36 contacting with the rear end of the thermostat 16 as at 42. This stopping or limiting of the valve member insures the proper positioning of the valve 35 in the port 28 at a predetermined water temperature.

But a single form of the invention is shown and described herein. However it will be understood that other forms and modifications may be made without departing from the spirit or scope of the invention.

Having thus described my invention, what I claim and desire to secure by Letters Patent is:—

85 1. A valve device comprising a casing having an inlet port and two outlet ports, one of said outlet ports being appreciably larger than the other, a valve for each of said outlet ports mounted to move towards its respective port against the direction of flow therethrough, and a thermostat connected to said valves so that the valve for the larger port is held shut and the valve for the smaller port is held open by the thermostat 90 when the latter is cold and the expansion of the thermostat causes an opening action of the valve for the larger port and a closing action of the valve for the smaller port.

100 2. A thermostat valve unit comprising a casing having an inlet and two outlet openings, one of said outlet ports being appreciably larger than the other, valves for said outlet openings, the smaller of said valves being slightly smaller than its opening and adapted to move bodily into and out of said opening to regulate the flow therethrough and the other of said valves being adapted to seat in closed position, and a thermostat connected to operate said valves.

105 3. A thermostat valve unit comprising a casing having an inlet and two outlets, a rod secured to the casing at one end and extending through one of said outlet ports and forming a guide, a thermostat secured to the other end of said rod, a cage surrounding said thermostat and secured to the free end thereof to be operated thereby, said cage having a part guided by said rod, and valves on said cage cooperating with said outlets.

110 4. A valve unit comprising a casing having a port, a rod secured to the casing and forming a guide, a cage guided by said rod, a thermostat in said cage secured to the rod at one end and to the cage at the other end, 115 and a valve on said cage for said port.

120 5. A valve device comprising a casing having a port, a rod secured to the casing and extending through said port, a valve of less diameter than said port sliding on said rod,

and a thermostat connected to operate said valve.

6. A valve device comprising a casing having a port, a rod secured to the casing and extending through said port, a valve of less diameter than said port sliding on said rod, and a thermostat supported by said rod and connected to operate said valve.

7. A valve device comprising a casing having a port, a rod secured to the casing and extending through said port, a valve of less diameter than said port sliding on said rod, said valve being adapted to move into and out of said port to regulate the flow there-
15 through, and a thermostat connected to operate said valve.

8. A valve unit comprising a casing having one end open and having an outlet chamber with a port near its other end, a rod secured to the casing and extending through said chamber and port, a thermostat secured to said rod, a cage surrounding said thermostat and secured to the free end thereof, a valve connected to said cage and controlling said port, and said cage controlling the open end of said casing.

9. A valve unit comprising a casing having an outlet chamber with a port, a rod secured to the casing and extending through said chamber and port, a valve for said port sliding on said rod, a cage secured to said

valve, and a thermostat in said cage and connected to said rod and said thermostat respectively.

10. A valve device comprising a casing having two outlet ports, valves for said ports, one of said valves being slightly smaller than its port and adapted to move bodily into and out of said port in regulating the flow therethrough, and the other of said valves being adapted to seat in closed position, means connecting said valves so that one is closed when the other is open and vice versa, and means for operating said valves.

11. A valve device comprising a casing having two separated outlet ports, interconnected valves for said ports arranged so that one valve opens as the other closes and vice versa, and a thermostat arranged in the casing in the space between the ports and connected to operate the valves.

12. A valve device comprising a casing having two separated outlet ports, valves for said ports, a cage arranged between the ports and connecting said valves so that one valve opens as the other valve closes and vice versa, and a thermostat in the cage and connected to operate the valves.

In testimony whereof I affix my signature. 60

ORMOND E. HUNT.
